(57) **CLAIM**

The ornamental design for a combination of personal enclosures, as shown and described.

DESCRIPTION

FIG. 1 is a perspective view of a combination of personal enclosures;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines shown within the claimed panels and cover of the combination of personal enclosures represent stitching, which forms a part of the claim. The zipper pulls and all other broken lines represent the environment in which the article resides and form no part of the claimed design.
